United States Patent Office

Des. 182,690
Patented Apr. 29, 1958

182,690

CHAIN SAW HANDLE

Lewis A. Scott, Portland, Oreg., assignor to
Omark Industries, Inc.

Application April 2, 1957, Serial No. 45,538

Term of patent 14 years

(Cl. D93—4)

FIG.1

FIG.2

FIG.3

FIG.4

FIG.5

FIG.6

Fig. 1 is an elevational view of one side of a chain saw handle embodying my new design;

Fig. 2 is an elevational view of the other side of the handle;

Fig. 3 is a front elevation of the handle;

Fig. 4 is a back elevation of the handle;

Fig. 5 is a top view of the handle; and
Fig. 6 is a bottom view of the handle.

I claim:

The ornamental design for a chain saw handle, as shown.
